UNITED STATES PATENT OFFICE.

SAMUEL H. DIXON, OF CONVERSE, SOUTH CAROLINA.

CONE-GAGE.

1,122,083.

Specification of Letters Patent. Patented Dec. 22, 1914.

Application filed March 20, 1914. Serial No. 826,070.

To all whom it may concern:

Be it known that I, SAMUEL H. DIXON, a citizen of the United States, residing at Converse, in the county of Spartanburg and 5 State of South Carolina, have invented new and useful Improvements in Cone-Gages, of which the following is a specification.

This invention relates to a cone gage and cutting attachment for yarn-winding 10 machines.

It is ordinarily the practice, in the operation of cone-winding machines, to gage the amount of yarn, which is being wound upon each core or tube, by the use of a gage stick, 15 so that the yarn may be severed whenever it appears that a sufficient quantity has been wound upon the core. This method is inaccurate and requires the expenditure of considerable time and labor in its performance. Absolute accuracy in determining 20 the amount of yarn wound upon each core is essential, in order that each cone may be of the correct size, and that all the cones may be uniform in this respect. Otherwise, 25 the cones could not be packed economically in the standard shipping cases provided for their reception, nor would they fit the machines in which they are to be used.

It is therefore the object of my invention 30 to provide a simply constructed and efficient attachment for winding machines of this description, which may be set to operate, when a predetermined quantity of yarn has been wound upon the core carried by the 35 spindle in connection with which it is employed, to cut the yarn at the proper instant and thus obviate the danger of too little or 40 too great an amount of yarn being wound upon any core.

The invention consists in the features of 45 construction, combination, and arrangement of parts, hereinafter fully described and claimed, reference being had to the accompanying drawings, in which:

Figure 1 is a side elevation of a portion 50 of a core-winding machine, showing the attachment in use thereon; Fig. 2 is a front elevation of the attachment alone on an enlarged scale, showing the cutting element 55 in its inoperative position; Fig. 3 is a side elevation of the same; Fig. 4 is a detail perspective view of the cutting apparatus; Fig. 5 is a perspective view of the gage device, showing the same mounted upon one 60 of the spindle supports of the winding machine; Fig. 6 is a vertical sectional view 65 taken through this portion of the device; Fig. 7 is a side elevation of the attachment as a whole, showing the cutting element in its operative position, as caused by actuation of the whirl of the gage device; and, 70 Fig. 8 is a side elevation of the crank shaft and the bearing member therefor of the connecting mechanism, the bearing member being shown partly in section.

In the drawings, I have illustrated the preferred embodiment of my invention, as it appears to me at this time, applied to a well known type of cone-winding machine, but it is to be understood that the device 75 may be employed in connection with numerous other kinds and makes of yarn-winding machines.

Referring to Fig. 1, in particular, it will be seen that each attachment includes, 80 primarily, a gage device A, a cutting device B, and the intermediate mechanism C which associates the devices A and B operatively with each other.

The gage device of each attachment is 85 connected with the supporting arm 1 of each spindle 2 of the winding machine and includes an attaching block 3, which is secured detachably upon the said arm by means of a set screw 4. The block 3 is provided with 90 a vertical, non-circular opening 5 in which the lower end of a vertical standard 6 is mounted and adapted to be secured by the set screw 7. A vertically adjustable slide block 8 having a non-circular opening 8^a receiving the standard 6 is mounted thereon and is adapted to be secured in adjusted 95 position by means of the set screw 9, the said standard being provided with a longitudinal scale of linear measurement which 100 is inscribed in suitable manner thereon, in order that the degree of adjustment of the slide block might be determined accurately. The use of this scale will be described more fully hereinafter. The slide block 8 is provided further with a circular, vertical opening 10 in which one depending arm 11 of an inverted U-shaped suspension member 12 is mounted for rotatable and vertically 105 slideable adjustment therein. A set screw 13 is mounted within the block 8 for use in securing the said arm of the member 12 in adjusted position within the receiving block opening. A bearing member 14 having a vertical opening 15 receiving the opposite 110 arm 16 of the suspension member is adapted to be secured in adjusted position thereon.

by means of the set screw 17. The rotatable shaft 18 of an actuating whirl 19 is journaled in the bearing block 14 with its axis parallel to the axis of the corresponding cone winding spindle 2. The whirl 19 is adapted to contact with the outer periphery of each cone as it is being wound upon its core, which is connected with the spindle 2, when the said cone has reached a predetermined size, whereby the whirl will be rotated for a purpose which will be described presently. A winding drum 20 is attached to the shaft 18 for rotation therewith.

Each cutting device includes a body 21, which is adapted to be secured to the winding machine adjacent to one of the yarn guides 22 by means of the clamp 23. A horizontal shaft 24 is rotatably mounted in the body 21 and is provided upon one end with a radial, oscillating arm 25 which is provided upon its free end with a lateral socket 26 in which the shank of a cutter blade 27 is adapted to be secured by means of the set screw 28. This blade is adapted, when in its normal, inoperative position, to underlie the stretch of yarn 29 leading from the corresponding guide 22 to the cone 30, which is being built upon the core carried by the corresponding spindle of the winding machine. It is to be understood that the blade is constructed of such length that the adjacent stretch of yarn will be disposed over some part of the blade at all times during its lateral shifting movement, as caused by any suitable form of transverse mechanism (not shown) which may be employed upon the winding machine.

A toothed pinion 31 is fixedly mounted upon the opposite end of the shaft 24 and has a radial, resetting arm 32 formed thereon. A longitudinally adjustable weight 33 is mounted upon the arm 32 and is adapted normally to maintain the said arm in its depending position, whereby the cutter blade 27 is maintained in its inoperative position beneath the stretch of yarn. A guide member 34 is formed upon the outer edge of a disk 34^a which is loosely mounted upon the shaft 24, the guide member being disposed outwardly of the outer periphery of the pinion 31, and a tangentially disposed rack bar 35 is mounted for reciprocation within the guide member with its teeth 36 meshing with the teeth 37 of the pinion. This rack bar 35 forms a part of the connecting mechanism C and has its upper end connected for longitudinal adjustment with relation to a parallel connecting rod 38, by means of the clamp member 39. The upper end of the connecting rod 38 is provided with a slot 40 receiving the crank pin 41 of a crank arm 42, the latter being fixedly mounted upon one end of a horizontal crank shaft 43. This shaft 43 is journaled in a bearing member 44, which is detachably mounted upon

the bar 45 of the winding machine, adjacent to the corresponding gage device by means of the clamp 46. The shaft 43 is arranged parallel to the shaft 24 of the corresponding cutting device and is provided on its opposite end with a radial crank lever 47. An oppositely extending resetting arm 48 is also formed upon this end of the crank shaft and is adapted normally to be maintained in depending position by means of the weight 49 which is adjustably mounted thereon. This arm thus serves to maintain the crank arm 42 and the lever 47 normally in their upwardly projecting inoperative positions. A flexible cord 50 has one end connected to the free end of the crank lever 47 and leads to the drum 20 of the whirl shaft 18, to the outer periphery of which its opposite end is connected.

The operation of the attachment associated with each winding element of the machine during the operation of winding a cone will now be described. The adjustable slide block 8 of the gage device is set initially in a predetermined position upon the standard 6, it being understood that the said standard is calibrated so that the slide may be set for a cone of a given number of ounces, of a given diameter, or containing a specified number of yards of yarn, the particular units of measurement employed being determined by the requirements of the art to which this invention relates. As the yarn is wound onto the core, which is attached to the winding spindle, the whirl 19 will be spaced from the outer periphery of the cone being wound, until the latter has reached the requisite mean diameter, whereupon the outer periphery of the whirl will become engaged with the cone so as to be rotated thereby. The flexible cord 50 consequently will be wound onto the drum 20 during this rotation, thereby operating the crank lever 47 to turn the crank shaft. This motion of the shaft is resisted by the counterbalancing weight 49 of the resetting arm, so that a definite amount of load is placed upon the whirl. This load, however, at first will not be sufficient to cause the whirl to slip and thus wear the yarn upon the cone, but, when the whirl has accelerated sufficiently, the crank pin 41 will have reached the lower end of the connecting rod slot 40, whereupon the load will be increased as the connecting rod and the attached rack bar 35 are thrust downwardly, imparting a semi-rotation to the shaft 24 of the cutting device. This movement of the shaft 24 will cause the arm 25 to oscillate downwardly and thus bring the cutter blade into engagement with the adjacent stretch of the traveling yarn, thereby severing the same. The counterweight 33 is adapted to resist this movement of the shaft 24 and serves to restore the same to its normal position, with the cutter blade in

operative, as soon as the rack bar is released. It is also to be understood that this winding machine is of the type wherein the cone-winding spindle will be checked at the instant the yarn is severed by any cause. The whirl of the gage device will thus cease to operate as soon as the cutting device has performed its operation, and the operative parts of the attachment will be reset automatically for use in connection with the next succeeding cone to be wound upon the spindle 2.

From the foregoing description, taken in connection with the accompanying drawings, it should be apparent that I have provided an attachment for winding machines, which may be set to sever the yarn, being wound upon each spool, automatically, after a predetermined quantity has been wound thereon, whereby all of the cones will be of exactly the same size. The respective gage devices upon a winding machine may be set to operate for different sized cones, so that different sized cones may be produced to meet the demand, without rendering it necessary for the operator to gage the different cones, as they are wound, with any manually operable gage device. It is to be understood, however, that my attachment is applicable not only to cone-winding machines, but to any other machine for winding bobbins, spools, or the like, the principle involved being the same in each instance. I also intend that minor changes in the details of construction, such as fall within the scope of the appended claims, may be resorted to in practice when found necessary.

What is claimed is:

- 40 1. The combination with a winding machine including a frame, a winding spindle mounted therein, and a yarn guide disposed in spaced relation to the said spindle, of a cutting device including a support mounted upon the frame adjacent to the said guide, and a movable cutting element carried by the said support, a gage device including a support mounted upon the frame adjacent to the spindle, and a movable member carried by the last-named support and being normally disposed in radially spaced relation to the spindle to be engaged and tripped by the cone to be wound thereon, means connecting the movable member of the gage device with the cutting element of the cutting device for causing coöoperative movement thereof, and yieldable means tending normally to maintain the cutting element in its inoperative position.
- 60 2. The combination with a winding machine including a frame, a winding spindle mounted therein, and a yarn guide disposed in spaced relation to the said spindle, of a cutting device including a support mounted upon the said frame adjacent to the said

guide, and a movable cutting element mounted upon the support, a gage device including a support mounted upon the frame adjacent to the spindle, a rotatable member journaled in the last-named support and being disposed in radially spaced relation to the spindle, and a winding drum connected with the said rotatable member, a supporting bearing mounted upon the frame adjacent to the gage device, a crank journaled in the said bearing and having a radial lever arm, a flexible cord having one end connected with the free end of the crank arm and its other end connected fixedly with the outer periphery of the said winding drum, and means connecting the crank with the movable element of the cutting device for movement therewith.

3. The combination with a winding machine including a frame, a winding spindle mounted therein, and a yarn guide disposed in spaced relation to the said spindle, of a cutting device including a support mounted upon the said frame adjacent to the said guide, and a movable cutting element mounted upon the support, a gage device including a support mounted upon the frame adjacent to the spindle, a rotatable member journaled in the last-named support and being disposed in radially spaced relation to the spindle, and a winding drum connected with the said rotatable member, a supporting bearing mounted upon the frame adjacent to the gage device, a crank journaled in the said bearing and having a radial lever arm, a flexible cord having one end connected with the free end of the crank arm and its other end connected fixedly with the outer periphery of the said winding drum, means connecting the crank with the movable element of the cutting device for movement therewith, the rotatable member of the gage device being adjustable radially with respect to the spindle, and means by which the said member may be secured against radial movement in adjusted position.

4. The combination with a winding machine including a frame, a winding spindle mounted therein, and a yarn guide disposed in spaced relation to the said spindle, of a cutting device including a support mounted upon the said frame adjacent to the said guide, and a movable cutting element mounted upon the support, a gage device including a support mounted upon the frame adjacent to the spindle, a rotatable member journaled in the last-named support and being disposed in radially spaced relation to the spindle, and a winding drum connected with the said rotatable member, a supporting bearing mounted upon the frame adjacent to the gage device, a crank journaled in the said bearing and having a radial lever arm, a flexible cord having one

end connected with the free end of the crank arm and its other end connected fixedly with the outer periphery of the said winding drum, means connecting the crank with the movable element of the cutting device for movement therewith, and yieldable means for normally maintaining the movable element of the cutting device in its inoperative position.

5 10 5. The combination with a winding machine including a frame, a winding spindle mounted therein, and a yarn guide disposed in spaced relation to the said spindle, of a cutting device including a support mounted upon the said frame adjacent to the said guide, and a movable cutting element mounted upon the support, a gage device including a support mounted upon the frame adjacent to the spindle, a rotatable member journaled in the last-named support and being disposed in radially spaced relation to the spindle, and a winding drum connected with the said rotatable member, a supporting bearing mounted upon the frame adjacent to the gage device, a crank journaled in the said bearing and having a radial lever arm, a flexible cord having one end connected with the free end of the crank arm and its other end connected fixedly with the outer periphery of the said winding drum, means connecting the crank with the movable element of the cutting device for movement therewith, and yieldable means for normally maintaining the movable element of the cutting device in its inoperative position the said crank being connected loosely with the movable element of the cutting device to permit of slight lost motion and to give the said crank lead on 25 the cutting element, and yieldable means for normally maintaining the said crank in its inoperative position.

30 35 40

6. The combination with a winding machine including a frame, a winding spindle mounted therein, and a yarn guide disposed in spaced relation to the said spindle, of a cutting device including a support mounted upon the said frame adjacent to the said guide, and a movable cutting element mounted upon the support, a gage device including a support mounted upon the frame adjacent to the spindle, a rotatable member journaled in the last-named support and being disposed in radially spaced relation to the spindle, and a winding drum connected with the said rotatable member, a supporting bearing mounted upon the frame adjacent to the gage device, a crank journaled in the said bearing and having a radial lever arm, a flexible cord having one end connected with the free end of the crank arm and its other end connected fixedly with the outer periphery of the said winding drum, means connecting the crank with the movable element of the cutting device for movement therewith, yieldable means for normally maintaining the movable element of the cutting device in its inoperative position the said crank being connected loosely with the movable element of the cutting device to permit of slight lost motion and to give the said crank lead on 50 the cutting element, and yieldable means for normally maintaining the said crank in its inoperative position.

In testimony whereof I affix my signature in presence of two witnesses.

SAMUEL H. DIXON.
